(57) **CLAIM**

The ornamental design for a bullet, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top plan view of the bullet;

FIG. 2 is a side elevation view thereof, the bullet being rotationally symmetric so the side elevation view is the same from all sides; and,

FIG. 3 is a perspective view thereof.
